UNITED STATES PATENT OFFICE.

CHARLES ARTHUR DAVIS, OF LOS ANGELES, CALIFORNIA.

SCARECROW.

1,357,032.

Specification of Letters Patent. Patented Oct. 26, 1920.

Application filed June 2, 1920. Serial No. 386,011.

To all whom it may concern:

Be it known that I, CHARLES A. DAVIS, a citizen of the United States, and a resident of Los Angeles, in the county of Los Angeles 5 and State of California, have invented a new and Improved Scarecrow, of which the following is a full, clear, and exact description.

This invention relates to improvements 10 in scarecrows, an object of the invention being to provide a scarecrow with movable arms which can be operated from a distance to make a noise and frighten away birds in gardens, fields and other places.

15 A further object is to provide an improved construction of scarecrow embodying a support and a pair of movable arms operating cymbals to sound an alarm when the arms are moved.

20 With these and other objects in view the invention consists in certain novel features of construction, and combinations and arrangements of parts as will be more fully hereinafter described and pointed out in the 25 claims.

In the accompanying drawings—

Figure 1 is a view in front elevation illustrating my invention.

Fig. 2 is a top plan view.

30 Fig. 3 is a view in side elevation.

1 represents an upright or standard which is rigidly fixed and secured in any desired manner and which is provided with a forwardly projecting, stationary or fixed arm 2.

35 A pair of movable arms 3, 3, are connected by spring hinges 4 with the standard or upright 1 and are normally held in substantial alinement with their ends 5 abutting against the sides of the upright or standard 40 1 by means of the spring hinges 4.

The stationary arm 2 is provided at its free end at opposite sides with a pair of cymbals 6, and cymbals 7 are secured to the free ends of the movable arms 3 so that 45 when said movable arms are swung inwardly toward each other, the cymbals 7 and 6 will be brought together to sound an alarm.

The fixed or stationary arm 2 is provided 50 with a pair of pulleys 8 and 9 mounted in openings 10 in said arm and said pulleys are preferably positioned at a slight angle to the longitudinal plane of the arm. A second pair of pulleys 11 and 12 are mounted 55 in openings 13 in the upper portion of the standard or upright 1 and a pair of

cords or flexible devices are passed over these pulleys to operate the movable arms 3 as will now be described.

One of these cords 14 is secured to an eye 60 or other fixed part 15 of one arm 3, is then passed around the pulley 9 and through a guide eye 16 on the fixed arm 2, and thence passed over the pulley 12 in upright 1. A second cord 17 is fixed to an eye or other 65 securing device 18 on the other movable arm 3, is then passed around the pulley 8, and thence over the pulley 11, and the ends of these cords 14 and 17 are joined through a single cord 18' which may be of any desired 70 length and extended to any point of operation.

It is, of course, to be understood that the cord or other flexible device 18' will have suitable mounting to maintain it off the 75 ground and reduce friction to a minimum and may be of a length to extend to the house of the owner so that it can be manually manipulated as occasion may require.

It is also obvious that the standard 1 and 80 the arms 3 may be utilized to receive a coat and an old hat may be provided on the upper end of the standard 1 so as to give the resemblance of a person standing in the field.

85 In operation, a pull on the rope or cord 18' will, through the medium of the cords 14 and 17, draw the free ends of the arms 3 toward the fixed arm 2 and bring the cymbals 6 and 7 together to make a noise and 90 frighten away the birds in the field.

It is obvious that other forms of noise 95 creating means might be employed, and various changes might be made in the general form and arrangement of parts described without departing from the invention, and hence I do not limit myself to the precise details set forth, but consider myself at liberty to make such changes and alterations as fairly fall within the spirit and scope of the 100 appended claims.

I claim:

1. A scarecrow adapted to be operated from a distance and comprising a fixed support, a pair of movable noise creating arms 105 connected to the support, a fixed arm on the support between the movable arms, and flexible devices for operating the arms from a distance, said flexible devices having guiding means in the fixed arm.

110 2. A scarecrow adapted to be operated from a distance and comprising a fixed sup-

port, a pair of movable noise creating arms connected to the support, a fixed arm on the support between the movable arms, flexible devices for operating the arms from a distance, said flexible devices having guiding means in the fixed arm, cymbals on opposite sides of the fixed arm, and cymbals on the free ends of the movable arms adapted to engage the cymbals of the fixed arm when moved against the same by the flexible devices.

3. A scarecrow adapted to be operated from a distance and comprising a fixed support, a pair of movable noise creating arms connected to the support, a fixed arm on the support between the movable arms, flexible devices for operating the arms from a distance, spring hinges normally holding the movable arms apart, and pulleys mounted

in the fixed arm and in the fixed support and serving as guiding means for the flexible devices.

4. A scarecrow, comprising a standard, a fixed arm projecting from the standard, a pair of movable arms, spring hinges connecting the movable arms with the standard and holding the movable arms in normal extended position, cymbals on the free ends of the fixed and movable arms, said fixed arm and standard having openings therein, pulleys mounted in said openings, and flexible connecting devices secured to the movable arms and passed over said pulleys and adapted to be moved longitudinally to draw the free ends of the movable arms toward the fixed arm.

CHARLES ARTHUR DAVIS.
